UNITED STATES PATENT OFFICE.

WILSON P. HUNT, OF MOLINE, ILLINOIS, ASSIGNOR TO BERNARD L. SCHMIDT, OF DAVENPORT, IOWA.

GRINDING-MACHINE.

1,281,015.

Specification of Letters Patent.

Patented Oct. 8, 1918.

Application filed March 13, 1918. Serial No. 222,104.

To all whom it may concern:

Be it known that I, WILSON P. HUNT, a citizen of the United States of America, and a resident of Moline, county of Rock Island, and State of Illinois, have invented 5 certain new and useful Improvements in Grinding-Machines, of which the following is a full and clear specification.

This invention has relation to that type 10 of grinding machines in which the spindle is carried by a rotating cylinder, means being provided for eccentrically adjusting the spindle with reference to the cylinder, to thereby give to the grinding-wheel a planetary movement, thereby adapting it especially to the grinding of the interior of cylinders and other hollow objects; and the 15 object of this invention is to improve and simplify the means for supporting the spindle and also for adjusting its eccentricity, as 20 more fully hereinafter set forth.

In the drawings—

Figure 1 is a side elevation of my improved grinding machine;

25 Fig. 2 is an end view of the head-stock, the spindle being removed;

Fig. 3 is a plan of the cylinder, showing the mechanism for regulating the eccentricity of the spindle;

30 Fig. 4 is a vertical section of the mechanism shown in Fig. 3;

Fig. 5 is an enlarged broken view in longitudinal section of the spindle, shaft, bearings, end cap and grinding-wheel seat;

35 Fig. 6 is a rear elevation of the cylinder; and

Fig. 7 is a perspective view of the swiveled guide-member.

In the drawings, the usual hollow cylinder 40

20 is journaled in the upper end of the usual head-stock, this cylinder being driven in the usual or any improved manner by means of a spur gear 21 formed on one end of the cylinder and meshed with suitable

45 gearing supported on the head-stock. Upon the rear end of the cylinder 20 is mounted a pair of flat faced lugs 22, through which extend two radial pivoted screws 23. Extending through the cylinder is the usual

50 spindle housing made up of two tubular sections 24, 25, the rear one of which has its rear end pivotally mounted on the afore-mentioned screws 23. The opposite sides of the housing section 24 are flattened to fit

55 squarely against the inner face of the lugs

22. The forward head of the cylinder is provided with a pair of forwardly-projecting flanges 26 whose inner faces are flat to engage the flat faces of the spindle housing 24, to thus serve in conjunction with the 60 flanges or lugs 22 to substantially support the spindle and accurately guide it in its radial adjustments. The means for adjusting the spindle radially are mounted on the forward head of the cylinder, so as to rotate 65 therewith. This means consists of a bar 27 suitably supported at its ends on the flanges 26 and having swivelly supported midway its length a graduated nut 28. Into the nut extends a threaded screw 29 whose inner 70 end is pivotally connected to the housing section 24, so that by turning the nut 28 the spindle may be moved back and forth across the axial center of the cylinder.

The sections 24 and 25 of the spindle 75 housing are secured together by screwing the forward section into the rear section 24, a bearing sleeve 30 being first screwed into the rear end of the section 25, this sleeve 30 serving as a mid-length bearing for the grinding-wheel shaft 31 which extends entirely through the housing sections. The gland-like sleeve 30 serves also to force into and hold in position an additional bearing sleeve 32, whose outer face is tapered forwardly to 80 correspond with the internal taper in the section 25. The forward end of the grinding-wheel shaft projects beyond the housing and is provided with suitable means for removably attaching a grinding-wheel thereto. 85

Another bearing is provided at the forward end of the spindle housing in the form of a rearwardly-tapering sleeve 33 fitted into the correspondingly tapered end of the housing section 25 and weighted firmly into 90 position by means of a cap 34 screwed onto the end of the housing. This tapered bearing 33 is provided with a longitudinal slot 35 for the reception of a lubricant-carrying wick or wiper, the lubricant being supplied to the bearing through a hole 36 in the housing section 25. At the rear end of the housing, the shaft 31 is provided with a shoulder 37 which faces rearwardly and abuts against the inner race-ring of an annular ball-bearing 38 fixed in the rear end of the housing section 24. Guide pulley 39 on the shaft 31 is affixed to the projecting end of the shaft, a nut 40 being threaded onto the end of the shaft to force the head of the pulley against 100

105

110

the inner raceway of the roller-bearing. The roller-bearing thus not only provides an annular or load bearing at the inner end of the housing, but also serves as a thrust bearing 5 for the grinding-wheel shaft.

The nature and scope of the invention having been thus indicated and its preferred embodiment having been specifically described, what is claimed as new is:

- 10 1. In a grinding machine of the class set forth, a cylinder journaled on the head-stock and provided with a pair of flat-faced members at its rear end and also a pair of flat-faced members at its forward end, a spindle structure extending through the cylinder and having the rear end of its housing fitted between the flat-faced members at the forward end and another part of its housing slidably fitted between the flat-faced members of the 15 forward end of the cylinder, and means for radially adjusting the spindle structure.
- 20 2. The structure recited in claim 1, said means consisting of a bar swivelly supported on the forward end of the housing, a nut swivelly supported in said bar, and a screw threaded through said nut and pivotally connected to the spindle housing.
- 25 3. A spindle structure for a machine of

the class set forth, consisting of a grinding-wheel shaft, a tubular housing therefor, a 30 bearing at the center of the shaft and at each end of the housing, the rear bearing being a roller-bearing and the rear end of the grinding-wheel shaft being provided with a shoulder engaging the inner raceway of said 35 roller-bearing, for the purpose set forth.

4. In a grinding wheel of the class set forth, a cylinder journaled upon the head-stock having a passage extending entirely through it, means for rotating this cylinder, 40 a tubular spindle casing extending through said cylinder and projecting at its forward end beyond said cylinder, means for pivoting the rear end of this casing at the rear end of the cylinder, means at the forward end of the cylinder for radially adjusting said tubular casing, a grinding-wheel shaft journaled in said tubular casing and extending therethrough provided at one end with a grinding wheel and at its other end with means whereby it may be driven, for the purpose set forth.

In testimony whereof I hereunto affix my signature.

WILSON P. HUNT.
